(57) **CLAIM**

The ornamental design for a hat measuring tape, as shown and described.

DESCRIPTION

FIG. 1 is a top front perspective view of a hat measuring tape showing my new design;

FIG. 2 is a front elevation view thereof, with the rear elevation view being a mirror image thereof;

FIG. 3 is a right elevation view thereof;

FIG. 4 is a left elevation view thereof;

FIG. 5 is a top elevation view thereof;

FIG. 6 is a bottom elevation view thereof; and,

FIG. 7 illustrates the hat measuring tape shown in use. The broken lines in FIG. 7 showing the hat measuring tape in use illustrates environment and forms no part of the claim.
